C. A. STEWARD

BUILDING BLOCK

Filed Nov. 20, 1920

FIG. 1

FIG. 2

FIG. 3

Charles A. Steward
INVENTOR.
BY Thomas G. Steward
ATTORNEY.

UNITED STATES PATENT OFFICE.

CHARLES A. STEWARD, OF PLANO, ILLINOIS.

BUILDING BLOCK.

Application filed November 20, 1920. Serial No. 425,412.

To all whom it may concern:

Be it known that I, CHARLES A. STEWARD, a citizen of the United States, and residing at Plano, in the county of Kendall and State 5 of Illinois, have invented certain new and useful Improvements in Building Blocks, of which the following is a specification.

The invention relates to building blocks 10 for use in concrete enclosures, such as corn cribs, wherein it is desirable to secure ventilation of the interior spaces to thereby relieve the contents of moisture and avoid deterioration thereof.

The object of the invention is, therefore, 15 to so fashion a building block that when it is laid in association with other building blocks to form the wall of an enclosure, ventilative ducts will be left in said wall through which air may freely circulate and carry off the moisture emanating 20 from the confined mass of material within the enclosure.

Concrete building blocks, as ordinarily 25 constructed, are provided with aligned vertical passages, the object being, not only to lighten the blocks and to save material, but to afford interior ventilation of the walls of which they are constituent elements, but in these blocks no provision is made for the 30 flow of air from the inside to the outside of structure, the walls of which are made tight to prevent cold outside air from reaching and cooling the enclosed spaces. The invention does not, therefore, concern building 35 blocks of this old type, except in so far as it may constitute an addition to or a qualification of building blocks of that kind.

In a specific embodiment of the invention, 40 there are formed in each of the building blocks, during the process of molding, not only vertical passages, such as are above described, but inner and outer inclined passages communicating with said vertical 45 passages, and affording free communication between the inside and the outside of the building, the object of the inclination of these passages being to present declivities which, respectively prevent the contents of 50 the enclosure from passing into the vertical ventilative passages, and the access of water from the outside.

These inclined passages are preferably 55 formed partly in one block, and partly in another block, so that when adjacent blocks are assembled, the individual portions of

said passages will coincide and constitute complete passages respectively establishing communication between the vertical ventilative passage and the interior and the exterior of the building.

The invention will be best understood by referring to the accompanying drawing, in which—

Figure 1 is a perspective view of a block 65 embodying one form of the invention;

Figure 2 is a fragmentary view of a wall embodying the invention and appearing in elevation; and

Figure 3 is a vertical sectional view, taken 70 on the line 3—3 of Figure 2.

Each block 1 is provided with one or more than one ventilative passage 2, and in the completed wall 3, there are inclined ducts 4 and 5 which respectively establish communication between the inside and the outside of a building and the ventilative passage 2.

One portion 7 of each of the ducts 4, 5, may be formed in the upper part of a lower 80 block, while another or mating portion 6, may be formed in the lower part of a superimposed block, the several blocks of a series being identically designed in order to effectuate economy in production and assembling.

The ducts 4, 5, are disposed opposite each other in the preferred form of the block, and they are spaced apart a sufficient distance to leave a considerable mass of cementitious material between them to resist a load. For the same reason said ducts are 90 separated from the ends of the block, as shown.

The wall of a building composed of blocks 95 embodying the invention, will securely retain stored masses of cereal and other products, and, at the same time, permit the access of air thereto. The inclination of the ducts 4 prevents particles of grain or ears 100 of corn from passing into the ventilative passage 2, while the declination of the outer ducts 5, likewise prevents water from entering said passage, although the circulation of air through said ducts and said passage is 105 freely permitted.

The portions 7 of the ducts 4 and 5, terminate at flat surfaces 8 which adjoin the ventilative passage 2 at the upper surface of a block, and the portions 6 terminate at 110 similar flat surfaces 8^a which adjoin the front and rear surfaces of a block at the

bottom thereof, thus avoiding thin edges which are liable to be broken.

The invention is not limited to the precise embodiment herein revealed, since it is ob-

5 vious that slight changes may be made, without departing from the principal of the invention, so long as inter-communication of the ducts is maintained and said ducts are so disposed as to exclude water 10 and, at the same time, prevent the escape of materials that are enclosed by the structure.

The blocks may be molded or otherwise fashioned, but molding is preferable if the 15 ducts are formed partly in one block and partly in another and adjacent block. In such case, the partial or semi-ducts are in effect recesses which admit of the withdrawal of the blocks from the molds.

20 Having thus described my invention, what I claim is:

1. A block having a vertical passage therein, and provided at top and bottom with inclined ducts extending from said 25 vertical passage through opposite side walls

of said block, said ducts being open and respectively adapted to mate with similar ducts in other blocks to form ventilative passages.

2. A block having a vertical passage 30 therein, and provided at top and bottom with inclined ducts extending from said vertical passage through opposite side walls of said block, said ducts being open and respectively adapted to mate with similar ducts in other blocks to form ventilative 35 passages, and merging at their inner ends with a horizontal surface of said block.

3. A wall composed of blocks arranged in staggered relations, said blocks each having a plurality of vertical passages, and each being provided with open channels at top and bottom communicating with said vertical passages from opposite sides of 40 said blocks, the passage at one end of a block being in alignment with the passages in the reverse ends of adjacent blocks.

45 In testimony whereof I affix signature.

CHARLES A. STEWARD.
